ATTACHMENT FOR GRINDING MACHINES

Alexander W. Keema, Providence, R. I., assignor,
by mesne assignments, to Bay Products Corporation,
a corporation of Massachusetts

Application April 4, 1944, Serial No. 529,493

10 Claims. (Cl. 51—166)

1

This invention relates to an attachment for a grinding machine, more particularly a surface grinder.

Attachments for grinding machines usually position the grinding tool in a plane some distance removed from the plane of the grinding wheel which is driven direct from the spindle when the attachment is not in use. Consequently, the full width of the table upon which the work is mounted is not available for use with the attachment.

One of the objects of this attachment is to provide an attachment mounting which will enable the tool of the attachment to be placed nearer to the plane of the grinding tool which is utilized on the grinding machine proper or in the plane where a greater amount of area of the table may be utilized for the work.

Another object of this invention is the provision of an adapter whereby the supporting bracket for the attachment may be arranged to embrace the spindle housing and be positioned inwardly from the end of the spindle.

Another object of this invention is to arrange a driving pulley to be located in substantially the same plane as that occupied by the main grinding wheel which would be mounted upon the spindle of the grinding machine.

With these and other objects in view, the invention consists of certain novel features of construction, as will be more fully described and particularly pointed out in the appended claims.

In the accompanying drawings:

Fig. 1 is a side elevation of a fragmental portion of the spindle and housing illustrating my attachment in place thereon;

Fig. 2 is an end view of the same;

Fig. 3 is an exploded view showing the various parts, some of which are in section, of the spindle, housing and the attachment which is positioned thereon;

Fig. 4 is a sectional view of the attachment, spindle and housing such as shown in Fig. 1; and

Fig. 5 is a sectional view taken on substantially line 5—5 of Fig. 4.

In proceeding with this invention the various parts of the attachment have been reformed and reassembled so that the driving pulley which is utilized is mounted directly on the end of the spindle with its driving surface arranged so as to be inwardly from the end of the spindle upon which it is mounted. To accomplish this an adapter is provided which is mounted on the spindle housing and arranged with a supporting bracket for the attachment tool shaft at a posi-

2

tion inwardly from the adapter and inwardly from the end of the spindle. Thus, everything is built inwardly from the end of the spindle instead of outwardly from the end of the spindle whereby the driving belt may be positioned in a plane to utilize a greater amount of table area than has heretofore been provided with attachment for grinding machinery of the character here dealt with.

10 With reference to the drawings, 10 designates the spindle of a grinding machine which projects through a sleeve housing 11 which is a part of the casing or framework of the machine. A conical portion 12 projects beyond the cylindrical end 13 of the spindle and has a mounting member 14 positioned thereon by means of the nut 15. This mounting member is utilized for the positioning of a grinding wheel on the spindle when desired.

20 The attachment parts which are provided consist of an adapter member designated generally 16, a bracket designated generally 17, a tool shaft housing unit designated generally 18, and a pulley designated generally 19, all of which are shown in exploded relation in Fig. 3.

The adapter designated generally 16 is generally annular in shape, having a body portion 20 with a central opening 21 therein of substantially the diameter of the spindle 13. This body portion is secured by means of screws or bolts 23 to the spindle housing 11 which is provided with threaded openings 24 to receive three or more screws 23 passing through the body and entering this spindle housing. This adapter has a rearwardly extending flange 24 projecting over the housing 11 with a wide face 25 and outwardly extending lugs or ears 26 which are threaded as at 27 for the mounting of the bracket 17 thereon.

30 The bracket 17 has a generally annular body portion 30 stiffened by a rib 31 extending radially outwardly therefrom with a central opening 32 which is of a size to permit this bracket to be loosely positioned over the housing 11 so as to encircle or embrace the same. This bracket is positioned about the spindle housing prior to the bolting of the adapter 16 in position. After the adapter is in position as above described the bracket is secured to the adapter by means of bolts 33 which extend through the lugs or outwardly extending ears 34 on either side of the bracket which are so located as to register with the lugs or ears 26 of the adapter. The lugs or ears 34 of the bracket are slotted as at 35 so as to accommodate the supporting bracket in various positions with reference to the adapter, the

bracket being bound in place by the bolt 33 in a desired position of adjustment. At the lower portion of the bracket 17 a mounting foot 36 is provided having threaded openings therein 37 to which the casing 38 of the unit 18 is attached by means of bolts 39 extending through the ears 40 which are on either side of this unit 18. In this unit 18 there is located a shaft designated 41 upon the end of which a tool 42 is mounted for operation on the work. A pulley or belt engaging surface 43 is provided on this shaft so that the same may be driven.

The pulley 43 is driven by the pulley 19 which consists of a body portion 45 having an opening 46 therein to receive the member 14 and be held securely on the member 14 by means of the nut 47 engaging the threaded portion 48 of this member thereby holding the same firmly on the spindle so as to be driven thereby. The body 45 is arched inwardly so as to provide the pulley cup shaped. The edge portion of the pulley is provided with spaced flanges 49 and 50 providing a belt driving surface 51 directly over and in the same plane with the pulley 43 so that a belt 52 may embrace the pulley 45 and the pulley 43 to drive the shaft 41 of the attachment from the spindle 13.

By the arrangement which is here provided securing the bracket inwardly a substantial distance beyond the end of the spindle and housing, and using such bracket with its built in portions and foot extending inwardly, unit 18 which carries the shaft for the tool is mounted much further inwardly from the end of the spindle than has heretofore been possible. Also by providing a pulley which is of generally cup shape so that its driving surface will be substantially over the adapter the plane of the drive of the belt is located a substantial distance inwardly from the end of the spindle. Further, by making the shaft 41 short where it extends outward beyond the casing 18 and driving this shaft close to the grinding tool a greater portion of the table upon which the work is usually mounted may be utilized than has heretofore been possible.

I claim:

1. In an attachment for a grinding machine an adapter member to be secured to the spindle housing, a bracket secured to said adapter to embrace the spindle housing inwardly from the outer extremity of the spindle, said member and bracket having the same center, a tool shaft rotatably carried by said bracket, a pulley carried by said tool shaft and positioned at a location substantially inwardly of the outer edge of said adapter member.

2. In combination with a grinding machine spindle and housing therefor, an adapter member secured to the spindle housing, a bracket secured to said adapter to embrace the spindle housing inwardly from the outer extremity of the spindle, said member and bracket having portions concentric with said spindle, a tool shaft rotatably carried by said bracket, a pulley carried by said tool shaft and positioned at a location substantially inwardly of the outer edge of said adapter member, a pulley secured to said spindle, and a belt embracing said pulleys whereby said spindle drives said tool shaft.

3. In combination with a grinding machine spindle and housing therefor, a grinding attachment wholly supported by said spindle and housing comprising an adapter member secured to the spindle housing, a bracket secured to said adapter to embrace the spindle housing inwardly from the outer extremity of the spindle, a tool shaft rotatably carried by said bracket, a pulley carried by said tool shaft and positioned at a location substantially inwardly of the outer extremity of the spindle, a pulley secured to said spindle at the outer end extremity thereof, and a belt

from the outer extremity of the spindle, a tool shaft rotatably carried by said bracket, a pulley carried by said tool shaft and positioned at a location substantially inwardly of the outer extremity of the spindle, a pulley secured to said spindle cupped to extend over said adapter member and a belt embracing said pulleys whereby said spindle drives said tool shaft.

4. In combination with a grinding machine 10 spindle and housing therefor, a grinding attachment wholly supported by said spindle and housing comprising an adapter member secured to the spindle housing, a bracket secured to said adapter to embrace the spindle housing inwardly 15 from the outer extremity of the spindle, said member and bracket having portions concentric with said spindle, a tool shaft rotatably carried by said bracket, a pulley carried by said tool shaft and positioned at a location substantially inwardly of the outer extremity of the spindle, a pulley secured to said spindle having a belt 20 engaging surface in line with said pulley on said tool shaft and a belt embracing said pulleys.

5. In combination with a grinding machine 25 spindle and housing therefor, an auxiliary grinding attachment wholly suspended from said housing comprising an adapter member secured to the outer edge of said housing and having a portion thereof positioned at a location substantially inwardly of the outer extremity of said housing, a bracket secured to the said portion of the adapter extending inwardly of the housing, a tool shaft rotatably carried by said bracket, a pulley on said shaft and positioned in a plane passing laterally through said adapter substantially inwardly of the outer edge thereof, a pulley on said spindle, and a belt embracing said pulleys whereby said spindle drives said tool shaft.

6. In an attachment for a grinding machine 40 an adapter member to be secured to the spindle housing at the outer edge thereof and cupped to extend over said housing, a bracket secured to said adapter to embrace the spindle housing inwardly from the outer extremity of the spindle, a tool shaft rotatably carried by said bracket, a pulley carried by said tool shaft and positioned at a location substantially inwardly of the outer edge of said adapter member.

7. In combination with a grinding machine 50 spindle and housing therefor, an adapter member secured to the spindle housing at the outer edge thereof and cupped to extend over said housing, a bracket secured to said adapter at the inner edge thereof so as to embrace the spindle housing inwardly from the outer extremity of the spindle, a tool shaft rotatably carried by said bracket, a pulley carried by said tool shaft and positioned at a location substantially inwardly of the outer edge of said adapter member, a pulley secured to said spindle at the outer end extremity thereof, and a belt embracing said pulleys whereby said spindle drives said tool shaft.

8. In combination with a machine spindle and 65 housing therefor, a grinding attachment wholly supported by said spindle and housing comprising an adapter member secured to the spindle housing, a bracket secured to said adapter to embrace the spindle housing inwardly from the outer extremity of the spindle, a tool shaft rotatably carried by said bracket, a pulley carried by said tool shaft and positioned at a location substantially inwardly of the outer extremity of the spindle, a pulley secured to said spindle at the outer end extremity portion thereof and cupped to extend over said adapter member and a belt

embracing said pulleys whereby said spindle drives said tool shaft.

9. In combination with a grinding machine spindle and housing therefor, a grinding attachment wholly supported by said spindle and housing comprising an adapter member secured to the spindle housing, a bracket secured to said adapter to embrace the spindle housing inwardly from the outer extremity of the spindle, a tool shaft rotatably carried by said bracket, a pulley carried by said tool shaft and positioned at a location substantially inwardly of the outer extremity of the spindle, a pulley secured to said spindle at the outer end extremity thereof and having a belt engaging surface in the line with said pulley on said tool shaft and a belt embracing said pulleys.

10. In combination with a grinding machine spindle and housing therefor, said spindle having

the extreme end portion thereof formed to receive an abrasive wheel thereon, an auxiliary grinding attachment wholly suspended from said housing comprising an adapter member secured to the outer edge of said housing and having a portion thereof positioned at a location substantially inwardly of the outer extremity of said housing, a bracket secured to the said portion of the adapter extending inwardly of the housing, a tool shaft rotatably carried by said bracket, a pulley on said shaft and positioned in a plane passing laterally through said adapter substantially inwardly of the outer edge thereof, a pulley on said spindle secured to the said extreme end portion thereof, and a belt embracing said pulleys whereby said spindle drives said tool shaft.

ALEXANDER W. KEEMA.
